TELEPHONE INTERCONNECTING CIRCUIT

Felix Strecker, Berlin-Steglitz, Germany, assignor to Siemens & Halske Aktiengesellschaft, Siemensstadt, near Berlin, Germany, a company of Germany

Application May 31, 1930, Serial No. 458,441, and in Germany June 22, 1929

3 Claims. (Cl. 179—15)

The present invention relates to interconnecting circuits for telephone lines or similar circuits. The invention has particular reference to the so-called conference type of connection in which 5 three or more subscribers' lines are interconnected so that each may communicate simultaneously with all the others.

An object of the invention is to associate three or more telephone or similar circuits by a simple 10 and direct scheme of interconnection providing conjugacy between the transmitting and receiving terminals of each line.

A feature of the invention is the use of an 15 interconnecting network in the form of a polygon in which the sides of the polygon are used for transmitting and the diagonals for receiving.

The polygon preferably has as many sides as there are circuits or lines to be interconnected. The impedances of the respective sides of the 20 network of polygon form are preferably equal and the impedances of the diagonals are also equal, thus providing mutually equal attenuation for all the subscribers.

Referring to the drawing, 25 Fig. 1 discloses a diagram showing the fundamental principle of interconnection according to the invention; and

Fig. 2 discloses one type of circuit for putting the principle of the invention into operation.

Fig. 1 shows a polygon of five sides although this polygon may be considered as having N sides where N is any odd number greater than four. The sides of the polygon h_1 to h_5 are intended in this figure to represent equal impedances which 30 are connected in series to form a complete polygon of impedances. The apices 1 to 5 are all connected with each other by diagonals r_1 to r_5 respectively.

If a source of E. M. F. is connected between the 40 adjacent apices, for example, the source h_1 between the apices 1 and 2, then all of the other (N minus 2) apices have the same potential, a potential which is mid-way of that between the points 1 and 2, that is, the points 3, 4 and 5 are each at the mid-potential existing between points 45 1 and 2.

The diagonal r_1 , therefore, connects points of equal potential (3 and 5) and is conjugate with respect to the source of E. M. F. in the side h_1 .

Each of the other diagonals r_2, r_3, r_4, r_5 , however, has impressed upon it an E. M. F. equal to one-half that of the transmitting source in the side h_1 .

If the transmitting terminals of a telephone line be connected in the side h_1 , therefore, and the 55 receiving terminals across the diagonal r_1 these

two sets of terminals are conjugate to each other. If the same scheme of connection is carried out for the four other lines the receiving branches r_2 to r_5 of the other lines will each receive an E. M. F. from the transmitting branch h_1 of the 60 first line.

In this way each line directly transmits to all of the other lines but there is no feed-back or return voltage appearing at the receiving side of any given line.

The scheme of interconnection shown in Fig. 2 follows directly from what has been described above of Fig. 1. Each of the five two-way lines l_1 to l_5 is provided with a corresponding balancing network n_1 to n_5 and hybrid coil a_1 to a_5 . The transmitting branch of each line is connected into one of the sides of the polygon, that is, in the position h_1, h_2 , etc. If desired, each such transmitting branch contains an amplifier v .

Each receiving branch leading to the hybrid coil a_1, a_2 , etc., is connected in a diagonal r_1, r_2 , etc., which may likewise, if desired, contain an amplifier v . As in Fig. 1, the receiving branch of each line is connected to the proper diagonal of the network to make the receiving branch conjugate with respect to the transmitting branch of that line.

The five sided polygon may also be used where only four subscribers' lines are to be interconnected. This may be done by replacing certain of the two-wire lines of Fig. 1 or 2 by suitable resistances or impedances which simulate an actual line. In Fig. 2, for example, line l_4 may be removed from the network by shifting the four switches s_1, s_2, s_3 and s_4 to their alternate contacts so that an impedance z_1 is substituted in diagonal r_4 for the transmitting impedance offered by line l_4 when present and z_2 is substituted in the side h_4 for the receiving impedance of the line. In the same way other lines may be disconnected and replaced by equivalent impedances. The principle of the invention illustrated and described in connection with Figs. 1 and 2 may, as already stated, be extended to a greater number of subscribers' lines than five. In this latter case also, diagonals or sides which it is not desired to use for the transmitting or receiving branches of a line may be replaced by suitably proportioned resistances.

What is claimed is:

1. A scheme of interconnection of more than three transmission circuits each having transmitting terminals and receiving terminals, in which the transmitting terminals of the circuits are connected in series to form a complete polygon.

having an odd number of sides greater than three, representing equal impedances, and the receiving terminals are connected across respective diagonal points, the diagonal across which a pair of receiving terminals are connected being that which will, in each instance, make the receiving terminals conjugate to the transmitting terminals of the same line.

2. An interconnecting circuit for five two-way telephone lines, each having a transmitting and a receiving branch, in which the transmitting

branches have their respective terminals connected in seriatim to form a complete polygon of equal impedances, and the receiving branches are connected to the appropriate diagonals to make the transmitting and receiving branches conjugate in the case of each line.

3. A system according to claim 1 in which certain of the impedances representing sides of the polygon are impedances substituted for actual lines.
